CLAIM

The ornamental design for a display screen or portion thereof with graphical user interface, as shown and described.

DESCRIPTION

The FIGURE is a front view of a display screen or portion thereof with graphical user interface showing our new design in a first embodiment.

The outer perimeter illustrated by a pair of broken lines in the FIGURE represents a display screen or portion thereof and forms no part of the claimed design. The remainder of

(Continued)

the broken lines illustrating portions of the graphical user interface forms no part of the claimed design.
